PRINT SUPPRESSION MECHANISM FOR CALCULATING MACHINES

Walter W. Landsiedel, deceased, late of Elmira, N. Y., by Florence E. Landsiedel, executrix, Cincinnati, Ohio, assignor, by mesne assignments, to Sperry Rand Corporation, New York, N. Y., a corporation of Delaware

Original application May 12, 1949, Serial No. 92,814. 10 Divided and this application September 2, 1953, Serial No. 378,151

4 Claims. (Cl. 235—60)

This invention relates to calculating machines wherein addition, subtraction, division, regular multiplication, short cut and discount multiplication problems may be performed, and has especial reference to means whereby the essential factors of such problems may be printed without the printing of unnecessary zeros.

The particular machine wherein the invention is embodied is an improvement on the machine disclosed in Patent 2,688,439, issued September 7, 1954, to Walter W. Landsiedel and entitled Decimal Point Mechanism, and it further improves upon the machines set forth in earlier Patents Nos. 1,899,444, 2,203,336, 2,229,980, 2,237,881, and 2,255,622.

This application is a division of application Serial Number 92,814 entitled "Adding and Computing Machines," filed May 12, 1949, by Walter W. Landsiedel, deceased, the inventor herein, and relates more particularly to mechanism herein for eliminating the printing of unnecessary zeros, particularly in multiplication and division problems.

In earlier machines, zeros required for spacing in the setting up of multiplication and division problems, were printed along with the factors of the problem on the tally sheet. The present machine does not print these zeros in either a multiplication or division problem. This is brought about by adding an extra row of space stops. These are used in place of the zeros formerly employed in the setting up of such problems. A row of these space stops has been added in front of the zero stops in the stop section of the machine. Novel mechanism cooperating with the adding racks and the space stops blocks the firing of the print hammers when the space stops are depressed. These stops are depressed by a space key and may be set up individually or by depressing the space key and a constant key simultaneously.

The object of this invention therefore is to provide a printing calculating machine in which there is means for preventing the printing of insignificant zeros, such as have been used in indexing in multiplication and division problems.

In brief and general terms, the invention herein is characterized by the combination of a print hammer, means for blocking the effective firing of said hammer, movable means to control the movement of the blocking means, and settable stop members to control the degree of movement of said control means.

More particularly there is provided a print hammer which is released in the cycle of operations to print; there is a blocking element, spring urged to effective blocking or unblocking position to prevent or permit the effective firing of the hammer; there is an adding rack unit provided with means, as the rack is moved rearward in the machine, to control the rearward movement of the blocking element; and there is a series of stops, operator manipulated, to regulate the degree of movement of the adding rack, one of said stops permitting the blocking element to move to blocking position, and the other stops

2

permitting the movement of the blocking element to unblocking position.

A preferred present form which the invention may assume is illustrated in the drawing, in which

5 Fig. 1 is a front to rear vertical section through the machine taken inside the right inner frame of the machine and showing certain basic features of the machine illustrating generally the location in the machine of the features of the invention;

Fig. 2 is a detailed perspective view of the zero non-print mechanism of the invention;

Fig. 3 represents a section of a tally sheet containing printed thereon a problem in division as performed and recorded on the machine of the present invention and involving the non-print of insignificant zeros;

Fig. 4 shows the same problem as in Fig. 3 as performed and recorded on a machine not having the novel mechanism for the non-printing of insignificant zeros;

Fig. 5 represents a section of a tally sheet containing printed thereon a problem in multiplication as performed and recorded on the machine of the present invention and showing the non-print of insignificant zeros; and,

Fig. 6 shows the same problem as in Fig. 5 as performed and recorded on a machine not having the novel mechanism for the non-printing of insignificant zeros.

The correspondence between the figures in this application and those of the parent application is as follows:

Present Application	Parent Application
Fig. 1	Fig. 8
Fig. 2	Fig. 12
Fig. 3	Fig. 13
Fig. 4	Fig. 14
Fig. 5	Fig. 15
Fig. 6	Fig. 16

Referring now merely to the specific form of the invention shown in the drawings, it is to be noted that in Fig. 1 a general section through the machine is illustrated and shows the stop carriage 10, in which is contained a group of stop pins 11 which are depressed or "set" by the stems 12 of digit keys 13 and provided with "space" stop pins 14 settable by means of the stems 15 of space stop key 16. The carriage 10 in normal inactive position is disposed at the right of machine so as to place the extreme left hand or highest order column of stop pins beneath the key stems. The carriage is tensioned to the left by spring means and escaped step by step by any suitable means each time a digit key 13 or a space stop key 16 is depressed and this action places a new column of pins beneath the key stems. Limited in the extent of their movement by the stop pins, which are set up by depression of the digit key or space key, are adding racks 17 located for longitudinal movement beneath the pin carriage 10. Each of these racks 17 is connected by pin 18 and slot 19 to an associated slide 20 formed with an upturned heel 21. These slides are held in their normal or forward position against the tension of a spring 22 by means of a bail rod 23 which is cam controlled as shown in Figs. 1, 4, and 6 of Patent No. 2,229,980 through arm 334, roller 331, and cam 315 of that patent. Each time the machine is cycled, the bail rod 23 moves rearwardly releasing and permitting the slides 20, and their associated racks 17, to follow upon the pull of spring 22 until their heels 21 limit against any stops 11 or 14 set up in the path of the heels of the respective slides. From Fig. 1 it will be noted that the space stop pins 14 are disposed in each column in front of all the other pins 11 which represent values from 0 to 9 inclusive, so that when a space stop pin is depressed the racks

cannot move to set the type racks to print any number. The purpose of the space stops is not only to index a space behind a figure entered into the pin carriage, but primarily to prevent the customary printing of insignificant zeros which would occur were it not for such space stops. Novel mechanism about to be described, associated with each of the several adding racks, prevents such zero printing in those columns wherein space stops have been actuated.

Referring now to the drawings, and particularly to Figure 2, there is shown one of the several adding racks 17 with its associated novel zero non-printing mechanism. Limited by its shoulder 24 against the ear 25 of a slide 20, is a rearwardly extending hammer blocking link 26 having a slot 27 at its forward end for guidance on a fixed cross bar 28. Projecting up from the rear of the link 26 is a type-hammer block arm 29. The link 26 is guided for longitudinal sliding movement by a tail 30 at its rear end slidable in a suitable slot in a fixed member 31. An ear 32 on the projecting hammer-block arm 29, when positioned in the clockwise path of movement of the type hammer toe 33, serves to block effective firing of the type hammer 34 and thereby prevents printing.

It will be seen that on the rearward stroke of the mechanism after a space stop 14 has been set up in the stop carriage 10, that the rack-carrying slide 20, under tension of its spring 22, moves rearward until stopped when its heel 21 limits against the set-up space stop. The slide 20 in sliding rearward removes its limiting ear 25 from the shoulder 24, whereupon the hammer block link 26, tensioned by its spring 26', is drawn rearward to a position wherein the block arm ear 32 is disposed under the print hammer toe 33 to prevent effective firing of the hammer. Upon the setting of any stop 11 rearwardly of the space stops 14, the hammer blocking link 26 will be permitted to move rearwardly sufficiently to carry the block arm ear 32 out of the path of the print hammer toe 33 and thereby permit effective hammer firing.

Now, to illustrate what occurs on a tally sheet where printing is prevented after space stops instead of zero stops have been indexed behind a figure entered into the pin carriage, reference is made to Figs. 3 and 5 showing, respectively, printed examples of a division and a multiplication problem performed on a machine where space stops and zero non-print mechanism is incorporated, and to Figs. 4 and 6 showing, respectively, printed examples of the same problems performed on a machine not having such improved mechanism.

The division problem (Fig. 3) is set up as follows: In the machine having the zero non-print mechanism, the dividend 468,790 is first entered into the pin stop carriage in the usual manner. The space key is then depressed four times, setting up four space stops, and the dividend so indexed is entered into the accumulator. Next the divisor 3750 is set up and the space key is depressed six times setting up six space stops to locate the divisor directly under 4687 of the dividend. In a machine not having the space stop and associated zero non-print mechanism, zero stops are indexed in lieu of space stops in setting up the dividend and the divisor.

The multiplication problem (Fig. 5) is set up as follows: In the machine with the zero non-print mechanism the multiplicand 37520 is first entered into the pin stop carriage. The space key is depressed three times setting up three space stops. In a machine not having the space stop and associated zero non-print mechanism, zero stops are indexed in lieu of space stops in setting up the problem.

It will be noted from Figs. 4 and 6, in the cases where the zero stops have been indexed, that such insignificant zeros have been printed in the performance of the problem, whereas in the examples in Figs. 3 and 5, where the space stops have been indexed, such insignificant zeros were not printed.

While having described what is considered to be a high-

ly desirable embodiment of the invention in this case, it is obvious that many changes in form could be made without departing from the spirit of the invention, which is, therefore, not limited to the exact form herein shown and described, nor to anything less than the whole of the invention as hereinbefore set forth, and as hereinafter claimed.

What is claimed is:

1. In a machine of the class described, a print hammer released to print in the cycle of operations, a blocking element for the print hammer, a spring to urge said blocking element to blocking or unblocking position to prevent or permit the effective firing of the hammer, an adding rack unit, means associated with said unit as it is moved rearward in the machine to control the rearward movement of the blocking element, and a stop carriage having key operated stop pins to regulate the degree of movement of the rack unit, one of said stop pins permitting the rack so to move that the blocking element moves to blocking position, and another of said stop pins permitting the rack so to move that the blocking element moves to unblocking position.
2. In a machine of the class described, the combination of print hammers, means for blocking effective firing of said hammers, an adding rack associated with and controlling the movement of said blocking means, a stop carriage, key operated space stops settable in such carriage for limiting movement of said blocking means to hammer blocking position, and key operated digit stops settable in said carriage for allowing movement of said blocking means beyond hammer blocking position to enable effective hammer firing.
3. In a machine of the class described, the combination of main operating means, adding racks and racks carrying type elements, print hammers operable by the main operating means for striking the type elements, print hammer blocking means associated with the adding racks, said adding racks being rearwardly movable by the main operating means and controlling the movement of the blocking means to and out of blocking position, a stop carriage, space stops settable in said carriage for limiting the rearward movement of the adding racks whereby on the limited movement allowed by the space stops the blocking means is permitted to move to hammer blocking position, and digit stops settable in the carriage for allowing movement of the adding racks beyond the space stops whereby the blocking means is permitted to move beyond hammer blocking position.
4. In a machine of the class described, a print hammer having a toe and adapted to be swung rearwardly to print, main operating means for releasing the hammer for printing operations, a blocking link having a blocking ear to be disposed in the path of the hammer toe, a spring for urging the link rearwardly, an adding rack unit including a slide and adapted to have a normal forward position, an ear on said slide blocking the rearward movement of the link when the slide is in its forward position, said rack unit being moved rearwardly by the operation of the main operating means, a pin stop carriage having digit stop pins and space stop pins adapted to be manually depressed, a heel on the slide to engage said stop pins to control the rearward movement of the slide, the space stop pins positioned to permit the rack unit to move rearwardly to dispose the blocking element in the path of the toe of the hammer, the digit stop pins positioned to permit the rack unit to move rearwardly to dispose the blocking element beyond the toe of the hammer and thereby permit effective firing of the hammer.
